COMBINED CIGARETTE CASE AND LIGHTER

Joseph Peters, St. Louis, Mo.

Application August 27, 1935, Serial No. 38,103

1 Claim. (Cl. 206—41.4)

This invention relates to a combined cigarette case and lighter, and has for the primary object the provision of a device of this character which will provide in one unit, storage for the entire number of cigarettes sold in a conventional type of cigarette package and which will present cigarettes one at a time to an ejecting means whereby each cigarette may be projected partly from the case to be placed in a person's mouth for lighting by the lighter, the latter being automatically operated by the actuation of said ejecting means.

With these and other objects in view, this invention consists in certain novel features of construction, combination and arrangement of parts to be hereinafter more fully described and claimed.

Figure 1 is a vertical sectional view illustrating a combined cigarette case and lighter constructed in accordance with my invention.

Figure 2 is a transverse sectional view illustrating the same.

Figure 3 is a perspective view illustrating a rack supporting cigarettes in the case.

Figure 4 is a fragmentary perspective view, partly in section, showing the means of mounting the rack in the case.

Figure 5 is a fragmentary sectional view showing the ejecting means and a cigarette partly ejected from the case ready to be placed in a person's mouth for lighting by the lighter.

Figure 6 is a sectional view taken on the line 6—6 of Figure 1.

Referring in detail to the drawing, the numeral 1 indicates a cigarette case composed of companion sections joined by a hinge 2. The companion sections may be retained in case formation by any suitable catch mechanism. One of the sections has mounted therein a lighter mechanism 3, including a fuel tank 4, one wall of which cooperates with an inclined wall 5 of the other companion section in forming a passage 6.

A cigarette rack 7 is mounted in the case 1 for the purpose of feeding cigarettes to the passage 6. The rack 7 includes a partition 8, side walls 9 and a bottom wall 10. The partition 8 is chambered and opened outwardly through the bottom wall 10, as shown at 11, for the reception of a tongue 12 carried by the hinge 2. The tongue 12 releasably secures the rack 7 in the case. The side walls 9 project beyond each side of the partition 8 and are flanged, as shown at 13. Spring-pressed followers 14 operate between the side walls at opposite sides of the partition. Cigarettes are arranged or stacked upon the follow-

ers upon opposite sides of the partition and one stack of cigarettes abuts the fuel tank 4, as shown in Figure 2 while the other stack of cigarettes is in align with the passage 6 so that the uppermost cigarette in the passage will be in proper position to be engaged by an ejecting means 15. The companion sections of the case are notched so that when closed they present a cigarette discharge opening through which the uppermost cigarette may be ejected by the ejecting means when actuated. When one stack of cigarettes in the rack has been exhausted, the rack is removed from the tongue 12 and reversed in the case so as to present the other stack of cigarettes in align with the passage 6. Thus it will be seen that the rack will permit the case to accommodate the entire number of cigarettes now sold in a conventional type package. Further, it is to be noted that the followers 14 are pressed downwardly in the rack when the cigarettes are stacked therein so that as a cigarette is ejected or removed from the case the next cigarette in the stack is presented in position for ejection.

The lighter mechanism 3 is of the type employing a fuel wick 16 which becomes saturated with fuel from the tank 4 and is lighted by the rotation of a serrated wheel 17 engaging with carbon 18 carried by a carbon holder 19. A cover 20 closes the lighter and the pivot of the cover is shown at 21, which forms a journal for the serrated wheel 17. A spring 22 acts to swing the cover into an open position and during this movement of the cover, rotation is imparted to the serrated wheel by a dog or tongue 23 engaging with said wheel and carried by the cover. The cover is equipped with an apertured keeper 24 engaged by a spring pressed slidable rod 25 forming a part of the ejecting means 15.

The ejecting means includes a slidably mounted plate 26 carrying an offset finger 27 adapted to engage behind the uppermost cigarette for moving the latter outwardly of the case. A finger piece 28 is secured to the plate 26 and projects through a slot in the case whereby said plate may be manually moved against the action of a spring 29. The plate 26 is slidably mounted on a rod 30 and said rod also forms a support for the spring 29 with one end thereof bearing against the plate 26. The plate 26 has a limited sliding movement which is sufficient to bring about ejection of the uppermost cigarette, as shown in Figure 5, so that said cigarette may be placed in the mouth. The movement of the plate 26 to eject the cigarette as described, en-

gages a projection 30 on the rod 25 causing a sliding movement of the rod to disengage from the keeper 24 and thereby free the cover 20 of the lighter. The spring 22 then acts to swing the cover and thereby bring about lighting of the wick 16. The person drawing upon the cigarette, as shown in Figure 5, may light said cigarette from the flame of the lighter.

Having described the invention, I claim:

10 In a cigarette case composed of companion sections and a hinge connecting said sections, a tongue connected to said case by the hinge, a rack including a partition and end members

thereto, and said partition having a chamber to receive the tongue for releasably mounting the rack in the case, flanges formed on the end members, said partition, end members and flanges cooperating in forming spaces for the reception of cigarettes arranged in superimposed relation at opposite sides of the partition, and spring pressed followers acting on the cigarettes and located at opposite sides of the partition and guided by the end members and the flanges.

10

JOSEPH PETERS.
